UNITED STATES PATENT OFFICE.

ELIZA A. HARRINGTON, OF LYNDHURST, NEW JERSEY, EXECUTRIX OF CHARLES F. HARRINGTON, DECEASED, ASSIGNOR TO THE DIAL VOTING MACHINE COMPANY, OF LYNDHURST, NEW JERSEY, A CORPORATION OF NEW JERSEY.

BOOTH FOR VOTING-MACHINES.

No. 806,137.

Specification of Letters Patent.

Patented Dec. 5, 1905.

Original application filed October 10, 1904, Serial No. 227,800. Divided and this application filed February 1, 1905. Serial No. 243,776.

To all whom it may concern.

Be it known that I, ELIZA A. HARRINGTON, a citizen of the United States, residing in Lyndhurst, in the county of Bergen and State of New Jersey, executrix of the last will and testament of CHARLES F. HARRINGTON, deceased, late a citizen of the United States, declare that the said CHARLES F. HARRINGTON invented a certain new and useful Improvement in Booths for Voting-Machines, of which the following is a specification.

The invention relates to portable curtain-booths adapted for service with voting-machines, and is especially designed to serve with a machine having a vertical shaft adapted to be partially rotated and again returned by the act of registering a voter's choice and conditioning the machine for the next voter. Such a machine is shown and described in an application by the same inventor, filed October 10, 1904, Serial No. 227,800.

The object of the invention is to provide a light portable booth easily set up and removed which shall conceal the voter and machine during his selection of candidates and registration of his choice.

The invention consists in certain novel features and details of construction by which the above objects are attained, to be hereinafter described.

The accompanying drawings form a part of this specification and show a preferred arrangement of the invention.

Figure 1 is an elevation of a voting-machine within the improved booth, a portion of the curtain being omitted. Fig. 2 is a corresponding plan view. Fig. 3 is an elevation, partly in vertical section, showing the upper portion of the frame of the booth on a larger scale. Figs. 4 and 5 are plan views showing details.

Similar letters of reference indicate the same parts in all the figures.

The voting-machine shown is of circular or turret form (marked A) and has a vertical shaft and operating-lever G⁴, by which the registration, resetting, and other operations are performed. The machine illustrated in the present application is the same as that shown and described in the above identified application and need not be specifically described.

For the purposes of this description it is sufficient to state that the voter finds the operating-lever in the position shown in Figs. 1 and 2, and in order to vote and condition the machine for the next voter he swings the lever through a semicircular arc and back again, causing a corresponding half-revolution and return of the shaft.

Upon the upper end of the shaft is fitted a tube or standard S, forming a vertical extension thereof and turning therewith. At the upper end is fixed a flange S⁷, having a series of openings s arranged annularly therein, and at the mid-height of the tube is secured a series of sockets S², corresponding in number to the openings above. Eight are shown.

S²S⁷ are arms of light but stiff wire bent at the mid-length, as shown, and having their ends each engaged in one of the sockets. S³S³ are links of similar wire hinged to the arms S²S⁷ at the angles in the latter and having hooks or bent-over portions S⁸ engaged in the openings s, producing, in effect, if properly proportioned, a series of radial horizontal arms and inclined braces. A cord or wire S⁶ extends from the outer end of each arm to the next, upon which is hung a curtain S⁶ of closely-woven fabric or other material sufficiently impervious to conceal objects behind it. Excepting the space or opening at S⁹ between two adjacent arms the curtain extends completely around and falls nearly or quite to the floor.

The machine is preferably placed in the corner of the room or voting-place, as indicated in Fig. 2, with the opening S⁹ near the wall S¹⁰. The voter entering the booth finds the lever G⁴ conveniently presented and pushes it before him through a half-circle to a stop (not shown) on the machine, correspondingly turning the shaft and its attached standard and arms through a half-revolution, thus bringing the opening S⁹ next to the wall S¹¹ and into the corner, in which position his movements within the booth in selecting candidates and conditioning the machine to record his choice are concealed. In leaving the booth he reverses the movement and leaves the opening S⁹ in the original position ready for a succeeding voter.

The standard S and arms S', with their attached links S³ and curtain S⁶, are easily put in position on the voting-machine in setting up the booth and may be readily folded and 5 packed for storage when not in use.

Although the booth is especially intended for service with the machine shown, it will be understood that it will serve with other machines and that the several parts and also 10 the sizes and proportions may be varied as required in adapting them to such service.

Having thus described the invention, what is claimed as new, and desired to be secured by Letters Patent, is—

- 15 1. In a booth for a voting-machine, a vertically-arranged shaft and means for turning it, a standard carried by such shaft, a frame supported by such standard and turning therewith, a curtain suspended from said frame and 20 having an opening, the said frame and curtain arranged to present said opening for easy ingress when the shaft is in one position, and to carry said opening to an adjacent wall when the shaft is partially rotated, and to return 25 said opening to the original position when said

shaft is turned to permit the egress of a voter and condition the booth for a succeeding voter.

2. In a booth for a voting-machine, a vertical shaft and means for turning it, a removable standard carried by said shaft and forming 30 an extension thereof, a series of sockets on said standard, a flange having a series of apertures at the upper end of said standard, a series of arms having their inner ends received in said sockets, a series of links each hinged to 35 one of said arms and having its free end engaged in one of said apertures, and a curtain suspended from said arms and adapted to move with the latter and said standard and shaft.

In testimony whereof I have signed my name to this specification in the presence of two subscribing witnesses.

ELIZA A. HARRINGTON,
*Executrix of the last will and testament of
Charles F. Harrington, deceased.*
